CLAIM

The ornamental design for a reconfigurable front grille for an automotive vehicle, as shown and described.

DESCRIPTION

FIG. 1 is a front perspective view of a reconfigurable front grille for an automotive vehicle, of the new design;

FIG. 2 is front view thereof;

FIG. 3 is a side view thereof;

FIG. 4 is a side view thereof, opposite that of FIG. 3;

FIG. 5 is a bottom view thereof;

FIG. 6 is a top view thereof; and,

FIG. 7 is a front view thereof, shown in an alternate configuration thereof.

The broken line showing of a vehicle is included for purpose of illustrating environmental subject matter and forms no part of the claimed design.

1 Claim, 7 Drawing Sheets
